UNITED STATES PATENT OFFICE.

JOSEPH WINDLE, OF SPOKANE, WASHINGTON.

SHOW-WINDOW FASTENER.

No. 909,267.

Specification of Letters Patent.

Patented Jan. 12, 1909.

Application filed May 21, 1908. Serial No. 434,094.

To all whom it may concern:

Be it known that I, JOSEPH WINDLE, a citizen of the United States, residing at Spokane, in the county of Spokane and 5 State of Washington, have invented certain new and useful Improvements in Show-Window Fasteners; and I do declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

My invention relates to the class of show cases, but more particularly to a fastener for securely holding together and in proper position the contiguous edges of two plates of 20 glass.

A further object of my invention is to provide a fastener for show cases, show windows or the like, which is so constructed and arranged that all tendency to break the glass 25 on tightening the fastener is entirely obviated.

A further object of my invention is to provide a fastener of this class which can be applied to plates of glass of any thickness.

30 A further object of my invention is to provide a fastener of this class which will allow for any degree of adjustment without pressing against the glass or in any way tending to grasp the same.

35 A further object of my invention is to provide a fastener of this class which allows for tightening the connecting bar without causing any pressure on the glass.

40 A further object of my invention is to provide a fastener of this class which cannot be removed from the outside of the show case or show window.

45 A further object of my invention is to provide a fastener of this class which cannot work loose on the inside or outside of the window or show case by the jar of doors or the like.

With all these objects in view my invention consists in the novel construction and 50 arrangement of the fastener; and my invention consists particularly in the construction which provides for tightening and locking the connecting bar without exerting any pressure on the glass.

55 My invention also consists in the construction of the connecting bar and in certain

other novel details of construction and in combinations of parts, all of which will be first fully described and afterwards specifically pointed out in the appended claims.

60

Referring to the accompanying drawing: Figure 1 is a perspective view showing the fastener applied to two plates of glass. Fig. 2 is an edge view showing the fastener in operative position. Fig. 3 is a similar view 65 showing one of the fasteners and a portion of one plate of glass in section. Fig. 4 is a plan and edge view of one of the loose washers, and Fig. 5 is an end view of one of the bolts.

Like numerals of reference indicate the 70 same parts throughout the several figures in which;

1 and 2 indicate the plates of glass to be fastened together and 3 indicates the fastener.

75

Referring to Figs. 2 and 3 it will be seen that the fastener 3 comprises two bolts 4 having heads 5, said bolts being threaded and each bolt being provided with two flattened sides 6, as clearly shown in Figs. 3 and 80 5. 7 indicates the connecting bar which, as shown in Fig. 1, is constructed in the form of a loop or link and bent substantially at right angles as shown in Figs. 2 and 3, each arm of the bar 7 straddling one of the bolts 6 as 85 clearly shown in Fig. 1. 8 indicates a threaded locking nut which, as shown in Figs. 2 and 3, lies adjacent the inner surface of the glass plates. 9 indicates a loose washer which, as shown in Fig. 4, is provided 90 with two transverse grooves 10, the bore or opening 11 of said washer being of such a size as to permit it to slide freely over the bolt 4. 12 indicates a threaded locking nut adjacent the loose washer 9 and designed to 95 lock said washer on the bolt 4 as shown in Fig. 3.

Having thus fully described the several parts of my invention its operation is as follows: After suitable holes have been drilled 100 through the glass plates to receive the bolts 4 the first locking nut 8 is threaded on each of the bolts 4 to such an extent as to prevent all binding or undue pressure against the inner surface of the plates of glass as clearly 105 shown in Fig. 2. The connecting bar 7 is then passed over the threaded end of each of the bolts 4 straddling the same, and the loose washer 9 is then placed on each of the bolts 4 in such manner that the transverse 110 grooves 10 in each of said washers register with the connecting bar 7 as clearly shown

in Figs. 1 and 3; the second locking nut 12 being then threaded on each of the bolts as shown in the drawing. The plates of glass being set up in their proper relative positions 5 and the connecting bar 7 being adjusted in order to maintain the plates in their proper relative position the first locking nut 8 is adjusted on the bolt 4 in such manner as to prevent all undue pressure on each of the 10 plates of glass. When this has been accomplished and the connecting bar 7 properly adjusted the second locking nut 12 is set up tightly against the loose washer 9, thus locking the connecting bar 7 rigidly between the 15 grooves 10 in the loose washer and the contiguous face of the first locking nut 8, as clearly shown in the drawing. It is therefore evident that any degree of pressure can be applied to hold the connecting bar 7 rigidly in position without exerting any pressure of the first locking nut 8 against the inner surface of the plate of glass. By this construction I am enabled to apply any degree of pressure against the connecting bar 7 20 without danger of breaking the glass, and to such an extent that the fastener will not work loose from the jar of doors or the like; while it is also evident that the fastener can not be removed from the outside as it is impossible to rotate the bolts 4 while the connecting bar 7 is in operative position thereon, 25 for the reason that the connecting bar 7 straddling each of the bolts 4 engages the flat side 6 of each of said bolts preventing any rotation of the bolts within the connecting bar 7. The transverse grooves 10 in the loose washer 9 registering with the connecting bar 7 maintain said bar in engagement 30 with the flat sides 6 of each of the bolts 4. 35 Having thus fully described my invention what I claim as new and desire to secure by Letters Patent of the United States, is:

1. A fastener of the character described, comprising two bolts, each of which is provided with two flat sides, a locking nut on each of said bolts, a link shaped connecting bar arranged to pass over the ends of said bolts, a loose washer having two transverse grooves therein arranged to be passed on 40 each of said bolts, the said grooves in each of said washers registering with the said connecting bar, and a locking nut for each of said bolts to lock each of said washers firmly in position and for the purpose of 45 maintaining pressure against the said connecting bar to hold same rigidly in position over each of said bolts.
2. A fastener of the character described comprising two bolts, each of which is provided with two flat sides, a link shaped connecting bar arranged to be passed over each 50

of said bolts, a loose washer arranged to be passed on each of said bolts and to engage said connecting bar, and a locking nut for each of said bolts for engagement with said loose washer on each of said bolts to hold each of said washers firmly in engagement with said connecting bar, substantially as described. 65

3. A fastener of the character described comprising two bolts, each of which is provided with a flat side, a connecting bar arranged to be passed over the end of each of said bolts, a loose washer arranged to be passed on each of said bolts and to engage said connecting bar, and a locking nut for each of said bolts for engagement with said loose washer on each of said bolts to hold each of said washers firmly in engagement with said connecting bar. 70

4. A fastener of the character described comprising two bolts, each of which is provided with a flat side, a connecting bar arranged to be passed over each of said bolts and to engage said flat side on each of said bolts to lock each of said bolts against rotation, means on each of said bolts for engagement with said connecting bar for locking said connecting bar firmly in position, and means on each of said bolts for relieving the objects to be fastened together from the pressure exerted on said connecting bar. 80

5. A fastener of the character described comprising two bolts, each of which is provided with a flat side, a connecting bar arranged to be passed over each of said bolts and to engage the flat side of each of said bolts to lock each of said bolts against rotation, and means on each of said bolts for engagement with said connecting bar, and further means on each of said bolts for securely locking said connecting bar in position. 85

6. A fastener of the character described comprising two bolts arranged to be passed through the objects to be fastened together, a connecting bar for connecting said bolts together, said connecting bar being arranged to be passed over each of said bolts and to engage same and lock each of said bolts against rotation, means for applying and maintaining pressure on said connecting bar to hold same rigidly in position, and means on each of said bolts for relieving the objects to be fastened together from the pressure applied and maintained on the said connecting bar. 105

In testimony whereof, I affix my signature, in presence of two witnesses.

JOSEPH WINDLE.
